UNITED STATES PATENT OFFICE.

FRANK P. J. PATENALL AND GEORGE H. DRYDEN, OF BALTIMORE,
MARYLAND.

AUTOMATIC BLOCK-SIGNAL SYSTEM.

No. 851,692.

Specification of Letters Patent.

Patented April 30, 1907.

Application filed December 4, 1906. Serial No. 346,238.

To all whom it may concern:

Be it known that we, FRANK P. J. PATENALL and GEORGE H. DRYDEN, citizens of the United States, residing in the city of Baltimore, Maryland, have invented certain new and useful Improvements in Automatic Block-Signal Systems; and we do hereby declare the following to be a full, clear, and exact description of the same, reference being had to the accompanying drawings, forming a part of this specification, and to the figures and letters of reference marked thereon.

This invention relates to automatic railway signaling systems being more especially though not exclusively applicable in connection with track circuits adapted to be shunted by the wheels and axles of a train or the opening of switches, etc. in the track section forming the block.

The objects of the invention are especially to effect a more positive, efficient and economical operation of the signal motor mechanisms, indicators, etc. even under adverse climatic or weather conditions. Also to provide a system not liable to be seriously affected by lightning discharges or the influx of heavy currents from extraneous sources. Also to provide a system wherein the signal lights will be so controlled as to give the highest efficiency and greatest economy, and as incidental thereto, to provide a system wherein the signal lights will be automatically lighted only when necessary or desirable to indicate the condition of the signals, as for instance, when there is an approaching train in one of the two preceding blocks or track sections. Also to provide a system so arranged that failure of the line connections between block or signal stations will still leave the system operative to permit a continuance of traffic with entire safety and under the control of properly operated signals normally included in the complete system.

The invention consists in certain novel details of construction and combinations and arrangements of the circuits and circuit connections and appliances appurtenant thereto all as will be hereinafter described and pointed out particularly in the appended claims.

In the accompanying drawings—Figure 1 is a diagrammatic illustration of a system embodying the present improvements and arranged for the operation or control of three position signals, each having one semaphore

arm and one lamp. Fig. 2 is a diagrammatic illustration of a portion of the system showing more especially the circuit arrangement for controlling or operating the distant relay of each block or signal station. Fig. 3 is a diagrammatic illustration of a system corresponding to the system illustrated in Figs. 1 and 2 but arranged for the operation or control of a plurality of semaphores and lamps or lights therefor, and from which it will be understood that any number of lights may be arranged in multiple and controlled from the same circuit.

Similar letters of reference in the several figures indicate the same parts.

In the system adopted for illustrating the present invention, traffic is supposed to proceed in one direction only, that is to say, from left to right as illustrated by the arrows in Figs. 1 and 2, although certain features of the system are equally applicable where traffic is to proceed in both directions over the same track, for instance, the automatic lighting of the signal lights in advance of a train and the extinguishing of such lights after the passage of the train. In both Figs. 1 and 3 four signal or block stations are shown, the circuit connections of the first and last stations however being incomplete, but as will be readily understood by those skilled in the art, the portions of the circuit connections and appliances not illustrated are merely duplicates of the corresponding portions of the circuit connections and appliances shown in the intermediate signal or block stations of the illustrations.

The block sections are indicated respectively, by the reference characters A' A² A³ and A⁴ and associated with each block section is a block or signal station preferably located with the semaphore or signal mechanism at the entrance to the block, the semaphores or signals being diagrammatically illustrated as is customary at S' S² S³ and S⁴ respectively.

B' B² B³ and B⁴ are track batteries, or other source of low voltage power, preferably located in proximity to the exit end of the respective track sections and adapted to energize track relays T' T² T³ and a corresponding track relay, not illustrated, the relay T being energized by a track battery, not illustrated, but forming a portion of the system corresponding to the portions illus-

trated as will be readily understood. Short circuiting of the rails or tracks between the batteries and track relays de-energizes the latter and through proper circuit connections controlled by said relays, in connection with circuit connections controlled by the signals, the signals themselves are operated to indicate to the engineer of each train, the track conditions existing for two blocks in advance of that on which the train is running and also operate or permit the signals in rear of the train to operate in a direction to indicate stop or danger.

The circuit connections and appliances may be briefly described as follows: C' C² C³ and C⁴ are clearing relays each controlled by two preceding track circuit sections. D' D² D³ D⁴ are distant relays for the control of the distant or clear indication of the signals S' etc., these relays being normally energized, but not with sufficient power to attract their armatures, except when the next succeeding signal is in either the clear or caution position. E' E² E³ E⁴ are double wound relays, E' being included in series in a circuit with D², E² being included in series in a circuit with D³ and E³ being included in a circuit in series with D⁴. Each is controlled by two sections of track circuit, as will presently appear. L' L² L³ and L⁴ are signal lights or lamps each controlled directly by the clearing relays C' etc. and the latter, as before stated, are controlled by two preceding track circuit sections whereby the signal lights will be lighted to show the condition of the semaphores or signals at two stations in advance of the train. F' F² F³ and F⁴ are batteries or other source of power for the control of the line relays, switch and tower indicators, which latter will be presently described. G' G² G³ and G⁴ are storage batteries from which power is derived for lighting the signal lights and operating the signal motors, signal operating clutches, locks &c. The latter parts are well known in the art and are therefore not illustrated, the circuit connections leading thereto being deemed sufficient for an understanding of the present invention. In this connection it may be stated that the controlling relays shown, are applicable for controlling practically any of the known systems of signal or semaphore operating motors, clutches, locks &c.

The storage batteries may be charged from a power circuit or from primary batteries or other suitable source of electrical energy and hence charging terminals are simply indicated in the diagram at W in the well understood manner.

In connection with the main block signaling system it is practical and desirable to make use of switch indicators, switch lamps, tower indicators, crossing bells, etc. and these parts are illustrated diagrammatically in the drawings, thus H' H² and H³ are

switch indicators, each controlled from two track sections namely, the immediate track section as well as the preceding track section. Indicator H³ is shown as an indicating relay carrying a local contact P for lighting switch lamp O from a local storage battery Q. I' I² and I³ are switch instruments for short circuiting the rails when switches are opened. R indicates a crossing or warning bell controlled by a tower indicator relay U and supplied with power from a battery V and it will be understood that the tower indicators U may give a visual indication to towermen, gatemen or station agents when trains are approaching.

N' N² N³ and N⁴ are circuit controlling devices always open to break the circuit when the semaphores or signals are at danger and closed by the said semaphores or signals when they reach the 45° or caution position to establish the circuit. They are held closed when the semaphore or signal moves to the clear or 90° position, thus the said circuit controlling devices are always closed to establish the circuits when the signals are in both caution and clear positions but are open to break the circuits when the semaphores or signals are in danger position.

Referring particularly to Fig. 2 it will be seen that the relays E' E² etc. are double wound relays, that is to say, the circuit may be established through all of the coils of said relay or a portion of the coils of said relay may be shunted or short circuited. This relay is wound to a high resistance, while the relay D² in series therewith, is wound to a low resistance, the proportioning being such that when the circuit flows through all of the coils of the relay E' the armature of relay D² will not be attracted, but when the circuit is established through a portion only of the coils of relay E', sufficient current will flow through the circuit to attract the armature of relay D² and render the same effective for controlling a motor circuit as will presently appear. The shunt for the coils of the relay E' is controlled by the circuit controlling devices N' etc. whereby the shunting is effected by the semaphores or signals. To better illustrate the operation of the system a train is presumed to occupy the block section A⁴ as indicated at X, the signal or semaphore at the entrance to the next succeeding section being at clear and the second succeeding semaphore or signal being at caution, all other semaphores or signals being at danger, but it being understood that all sections in advance of section A⁴ are unoccupied. Under these conditions, current from battery F' flows through the upper contact of track relay T, coils of relay E', line wire K² intermediate contact of track relay T', distant relay D² to common return wire M, thus energizing relay E' to attract its armature, but the relay D² being wound to a low resistance

its armature is not attracted. Current from battery F' passing through the said upper contact of track relay T' branches through front contact of relay E' through wire J' to a clearing relay corresponding to relay C' but at the next succeeding station, and therefore not shown, returning through common return wire M . At the block station for section A^2 , the conditions are somewhat altered 5 because of the fact that the semaphore or signal is at caution and the circuit closing device N^2 closed. At this station, current from battery F^2 flows through the upper contact of track relay T' , circuit closer N^2 operated by signal S^2 and closed because the latter is in caution position, through a part of the resistance in relay E^2 , to line wire K^3 , intermediate contact on track relay T^2 , coils of relay D^3 to common return wire M , a sufficient current flowing in this instance because 10 of the shunt at E^2 to cause the armature of the relay D^3 to be attracted, the conditions then existing being that the armatures of both relays E^2 , D^3 are attracted and the circuit connections controlled thereby established. Current from battery F^2 passing through the upper contact of track relay T' and branching through the front contact of relay E^2 passes to circuit wire J^2 and energizes switch indicator H' and relay C' in 15 multiple with each other, the return being effected through the common return wire M . At the signal station for the block A^3 the semaphore S^3 is at clear position and the circuit from the battery F^3 passing through the upper contact of track relay T^2 , circuit closer N^3 on signal S^3 , through a part of the coils of relay E^3 to line wire K^4 thence to intermediate contact on track relay T^3 , finds the latter 20 open because of the short circuiting of the track battery B^3 and no current flows. As a result relays E^3 and D^4 are de-energized and their armatures down. The branch of the circuit from the battery F^3 controlled by the relay E^3 being opened by the dropping of the armature of the relay E^3 , no current flows on the line J^3 and as a result switch indicator H^2 and clearing relay C^2 of the succeeding station are de-energized, switch indicator H^2 displaying danger, and through the back contact at P lighting the switch lamp O . Relay C^2 operates through suitable front and back contacts to perform several functions. First the dropping of the armature opens the front 25 contact to remove the shunts from the signal motor as will be presently explained. Secondly it gives current from the storage battery through its upper back contact, lower front contact of track relay T' to caution motor control Z through motor (not shown) and back to battery through the return motor control Z' thereby driving the signal S^2 to the caution position. Thirdly it gives current from the storage battery through the lower 30 back contact to the lamp or signal light L^2 thereby lighting the lamp for signal S^2 which latter is now in the caution position and illuminated. Relays T^3 and E^4 being de-energized no current passes from battery F^4 to the switch indicator H^3 , tower indicator U or clearing relay C^3 . Indicator H^3 therefore goes to danger by gravity, tower indicating relay U assumes danger position by gravity and gives current to the back contact of its armature from the battery V to the crossing bell and the armature of relay C^3 opens to perform the three functions of first, removing the shunt from the signal motor, secondly, giving current through its upper back contact and also front contact of track relay T^2 to caution 35 motor control Z through the motor and back to battery thereby driving the signal S^3 to caution position. Signal S^2 as well as signal S^3 now being in caution position and circuit controller N^2 closed shunting a part of the resistance of relay E^2 , the current in line K^3 is of sufficient strength to attract the armature of distant relay D^3 . Signal S^3 having already been driven to the caution position, we now have circuit conditions for permitting current from storage battery G^3 to pass through upper back contact of relay C^3 , lower front contact of track relay T^2 , branching through front contact on distant relay D^3 to clear motor control Z^2 and through said 40 motor driving the signal to its clear position. Thirdly, current from storage battery G^3 finds a path through lower back contact of clearing relay C^3 to lamp L^3 whereby the latter is lighted to illuminate the signal S^3 . 45 With train X occupying the block section A^4 and the track relay T^3 open, a following train entering track section A^5 or the next section preceding the section A^5 causes the clearing relay C^4 to open, current being immediately 50 given to light the lamp L^4 , although signal S^4 cannot operate on account of track relay T^3 being open and hence the danger conditions ahead of the following train are indicated both by the position and the lighting of the 55 signal. Under the illustrated conditions i.e., with a train occupying block section A^4 , it will also be noted that signal lamps L^2 and L^3 and switch lamp O are burning but lamps L^1 and L^4 are not lighted, signal S^2 is in the 60 caution position and signal S^3 in the clear position, switch indicators H^2 H^3 at the danger, switch indicator H^2 is clear, tower indicator U is at danger and crossing bell R is caused to ring. It will be noted that all track relays 65 T , T' etc. are so arranged that when energized they are in position to permit current to pass through the lower front contacts from the storage batteries to the signal motors and when deenergized the home or caution control 70 side of the signal motor is in shunt with the return motor control through the lower back contact. The shunting of the distant or clear motor control side of the signal motors or 75 clutches is controlled by the duplicate front 70

contacts of the relays C', C², C³, C⁴ both said shunts being effective at all times save when the motor or motors are being operated to move or hold the signals. The shunt circuits may be clearly seen in Fig. 1 at the left hand station A⁵ where the clear motor control Z² leads directly to one of the duplicate front contacts of the relay C⁴ and said relay C⁴ being energized the shunt circuit is completed through its armature and the other front contact of relay C⁴ to the motor control return Z'. From the caution motor control Z the shunt is established through the armature and back contact of track relay T³. This relay being deenergized and its armature against said contact establishes the shunt circuit to the motor control return Z' thus both motor controls are shunted or short circuited. When train X passes into block section A³ and out of block section A⁴, track battery B² is short circuited, thereby causing the track relay T² to be de-energized, (the signal or semaphore S³ immediately assuming the danger position) and opens the circuit through line wire K³ de-energizing relays D³ and E² and causing their armatures to drop. The dropping of the armature of the relay E² opens the circuit through the line wire J² thereby causing the indicator H' to go to danger by gravity and the armature of clearing relay C' to drop and remove the shunt from the signal motor for signal S'. Storage battery G' through the back contact of relay C' lights the signal light L', operates the motor to move the signal S' to caution, and the latter through the circuit controller N' shunts a part of the resistance in relay E' to increase the current in line K², the effect of which is to cause the armature of relay D² to be attracted giving current from the storage battery G' to the clear motor control and thereby changing the signal S² to the clear position. Track relay T³ closes as the train moves out of the section A⁴ thereby giving current from battery F⁴ through upper front contact of relay T³ coils of relay E⁴ to line K⁵ leading back to the track relay and distant relay of the preceding section not shown in the drawing, the return being effected through the common wire M and the result being to attract the armature of relay E⁴ thereby giving the current through the front contact of the latter to line J⁴ and energizing switch indicator H³ moving the same to clear position. The current in this circuit also attracts the armature of tower indicator U giving a clear indication, stops the bell from ringing and attracts the armature of relay C³ thereby extinguishing the lamp L³ for the signal S³, opens the motor battery circuit controlled by relay C³ shunts the motor through the front contact of said relay and the signal moves to danger. The return motor control it will be noted, is shunted or the motor or motors included in closed shunt circuits when the clearing relays

are closed or when the track relays are open, or in other words, when the signals are in the danger position which is the normal position, the motors are protected by short circuiting and hence the possible effect of stray or foreign currents on the signal motors or clutches is practically eliminated and the chances of interference by such foreign currents tending to cause the signals to stick in clear or caution position when they should be in the danger position as when the track relays are opened, is reduced to a negligible factor.

In Fig. 3 the circuits and operation of the system correspond in all respects to Figs. 1 and 2 the sole difference between the two systems being that in Fig. 3 two signals or semaphores are shown on the same post and hence two lamps are required for illuminating the respective signals or semaphores. In Fig. 3 lamp L⁵ is in multiple with lamp L', lamp L⁶ is in multiple with lamp L², lamp L⁷ is in multiple with lamp L³, lamp L⁸ is in multiple with lamp L⁴, the lamps being thus arranged in pairs and both lamps of a pair being simultaneously lighted when the circuit conditions are as heretofore described in connection with Figs. 1 and 2. It will be understood of course that the two semaphores or signal arms are operated just as is now common in the art where the double indication is desired rather than a three position indication. In this Fig. 3 the train is presumed to occupy the section A⁴, as heretofore described in connection with Fig. 1 and inasmuch as the operation is in all respects identical, further description is thought to be unnecessary, the illustration being mainly to show the applicability of the present invention in systems requiring a plurality of lights and in this connection it will be understood that the number of lights and signals may be increased at will.

From the foregoing description it will be seen that failure of the line wires between block stations will still leave an operative and safe signaling system, for instance, breakage of line wires J', J², etc., would cause the armatures of clearing relays C' C², etc., and switch indicators H' H², etc., and tower indicator U to drop and in turn the signal governed by the said relays to change to the caution indication and this would be the normal position in such signal. The lights controlled by any of the circuits would burn continuously until repairs were made and a train passing in the proper running direction would receive indications in either night or day, permitting the trains to proceed under caution signals but without interruption of traffic. In other words, the system is simply transposed into a normal caution system. So also should line wires K' K² etc. of common wire M be broken, relays E' E² etc. would open taking away power from clearing relays C' C² etc. as well as from the switch

- indicators and from line relay P and tower indicator. This in turn would also cause the signal governed by the clearing relay to change to the caution indication and the lights would burn continuously as before.
- 5 As in the other instance, a train passing in the proper running direction would receive a caution indication when the track relays were closed, and in every instance, the signals
- 10 will always display danger in rear of the trains and cannot be moved to the caution position until the train has cleared the track section. Under the conditions stated wherein all of the line wire connections have failed,
- 15 all lamps will burn continuously and the system is transposed into a normal caution system, the signaling mechanism proper including the semaphores, lights, caution motor control &c., all being operative and effective
- 20 and under the control of the track relays.
- Having thus described our invention, what we claim as new and desire to secure by Letters Patent, is:—
1. In a block signaling apparatus the combination with a series of normally closed rail circuits and circuit closers controlled by said circuits, of signaling circuits normally shunted by said circuit closers and adapted to be established to render the signals operative by the presence of a train on the track sections.
  2. In a block signaling apparatus, the combination with a series of normally closed rail circuits and circuit closers controlled by said circuits, of a series of signal circuits normally shunted by said circuit closers but established by said circuit closers when the rail circuits are shunted to render the signals operative.
  3. In a block signaling apparatus, the combination with a series of normally closed rail circuits and circuit closers controlled thereby, of indicator and clearing circuits normally established by said circuit closers and a series of signal circuits normally shunted by said circuit closers but established by said circuit closers when the rail circuits are shunted to render the signals operative.
  4. In a block signaling apparatus, the combination with a series of normally closed rail circuits and track relays controlled thereby, a circuit controlled by two successive track relays and including a distant and a preliminary relay in series, normally closed contacts controlled by the preliminary relay, a combined clearing and indicating circuit including the preliminary relay contacts and contacts controlled by a track relay, said two last mentioned circuits being interrupted when the rail circuits are shunted thereby preventing signals in rear of trains and indicators ahead of trains from clearing and also causing signals ahead of trains to clear when the track circuits ahead of trains are not shunted.

5. In a block signaling apparatus, the combination with a series of normally closed rail circuits and circuit closers controlled thereby, of indicator and clearing and distant circuits normally established by said circuit closers and interrupted thereby when the rail circuits are shunted to move the indicators to danger and prevent the clearing of the block signals.

6. In a block signaling system the combination of a series of normally closed and energized track circuit sections, circuit closers controlled thereby, distant relay circuits normally closed by said circuit closers and each including a distant relay and a preliminary relay embodying shunt coils normally in series and of such resistance as to prevent the operation of the distant relay, automatic signals having a preliminary or caution position controlled by the track section circuit closers, circuit closers controlled by the signals to shunt the preliminary relay coils, reduce the circuit resistance and render the distant relay operative to clear a signal previously moved to the caution position.

7. In a block signaling system the combination of a series of normally closed and energized track circuit sections, circuit closers controlled thereby, distant relay circuits normally closed by said circuit closers and each including a distant relay at the home station and a preliminary relay at a succeeding station embodying shunt coils normally in series and of such resistance as to prevent the operation of the distant relay, automatic signals having a preliminary or caution position controlled by the track section circuit closers, circuit closers closed by the signals when in caution and clear positions to shunt the coils of the preliminary relay, reduce the circuit resistance and render the distant relay at the home station operative and a clear signal operating circuit established by said distant relay to clear the signal when the said succeeding signal is in caution position.

8. In an automatic block signaling system, the combination of normally closed track circuit sections and independent normally open signal lighting circuits controlled by the track circuits, associated with mechanical signals rendered visible by the closing of the lighting circuits.

9. In an automatic railway block signaling system, the combination of a plurality of normally closed track circuit sections and a plurality of independent normally open signal lighting circuits each controlled by the immediate and next preceding track circuit sections whereby the signals are lighted a section in advance of that in which a train may be located and extinguished only after the train has passed out of the immediate section.

10. In an automatic railway block signal-

- ing system, the combination of a plurality of normally closed track circuit sections and a plurality of independent normally open signal lighting circuits each controlled by two sections of track circuit to light the signals during the presence of a train in either section. 70
11. In an automatic railway block signaling system the combination of a plurality of normally closed track circuit sections, circuit closers controlled thereby, normally energized relays corresponding in number to the track circuit sections and each controlled by two sections of track circuit and independent signal lighting circuits one for each relay and including a circuit closer normally held open through the action of said relay but released to close the lighting circuit when a train is in either of the controlling track sections. 75
12. In an automatic block signaling system, the combination of a plurality of normally closed track circuit sections, normally closed circuit closers controlled thereby, normally energized relays one for each section and included in a circuit controlled by two track section circuit closers, normally open independent local signal lighting circuits a circuit closer for each lighting circuit controlled by one of said relays and released to light the signal lights by opening of the relay circuit through the presence of a train in either of the controlling track sections or through failure of the line wires. 80
13. In an automatic block signaling system, the combination of normally closed track circuit sections, normally open lighting circuits, normally shunted signaling circuits and circuit closers controlled by the track circuits to close the lighting circuits and open the signal circuit shunts when the track circuits are shunted. 85
14. In an automatic block signaling system, the combination of normally closed track circuit sections, normally open lighting circuits, normally shunted signaling circuits, normally closed indicator and clearing relay circuits, and circuit closers controlled by the track circuits to close the lighting circuits, open the shunts of the signal circuits and open the indicator and clearing relay circuits when the track circuits are shunted. 90
15. In an automatic block signaling system the combination of normally closed track circuit sections, normally inoperative local signal circuits, normally closed distant and preliminary relay circuits, distant and preliminary relays in said last mentioned circuits and circuit closers controlled by the track circuit sections and distant relays for establishing the signal circuits to operate the signals. 95
16. In an automatic block signaling system the combination of normally closed track circuit sections, normally inoperative local caution and clear signal circuits nor- 100
- mally closed distant and preliminary relay circuits, distant and preliminary relays in said last mentioned circuits, circuit closers operated by the track circuits for establishing the relay circuits, circuit closers operated by the distant relay and by the track circuits for establishing the clear signal circuit, the circuit closers controlled by the track circuits also operating to establish the caution signal circuits independently of the distant relays. 105
17. In an automatic block signaling system the combination of a plurality of automatic signals normally indicating danger but adapted to indicate caution or clear and located respectively at the entrance to the blocks, local signal circuits for moving said signals to caution and clear positions, normally closed line circuits between stations including circuit controllers for the signal circuits whereby the movement of the signal at one station is dependent upon conditions existing at another station and circuit controllers at each station operated by the track section circuit for that block also controlling a signal circuit, and when the line circuits are broken or inoperative, operating to establish said signal circuit to hold the signal out of the danger position, but permitting it to move to danger when the track section is occupied. 110
18. An automatic block signaling system wherein the signals normally stand at stop or danger, track and line circuits operating to control the movement of said signals from danger to caution or clear positions in advance of an approaching train and also embodying signaling circuits controlled from the track circuits alone when the line circuits are broken or inoperative for holding said signals normally out of the danger position but permitting any signal to go to danger when the track section controlled by that signal is occupied by a train, the breaking of the line circuits thus transposing the system from a normal danger into a normal caution 115 or clear system. 120
19. In an automatic signaling system, the combination of a plurality of automatically controlled signals, normally indicating stop, normally closed track circuits shunted by a train in the immediate block section, normally closed distant control and preliminary relay circuits operated by two sections of track circuit, normally closed indicator and clearing relay circuits operated by a preliminary, and a track relay switch, normally shunted signaling circuits controlled by a clearing relay switch to remove the shunt and give power to the signal motor through an immediate track relay switch, to give a 125 caution indication and also to give power through an additional relay switch controlled by a second section of track circuit and a circuit closer on the signal in advance to give a clear indication. 130

20. In an automatic block signaling system, the combination of the track circuit sections including track relays a signal normally indicating stop located at the entrance to each block section and adapted to give a plurality of indications, signal motor control circuits for controlling the movement of the signal away from stop position and normally shunted, a clearing relay for removing the shunt from the signal circuit and giving power through the track relay switch to give a caution indication, a preliminary relay having two windings and a distant relay in series therewith but at the opposite end of the distant wire, the preliminary relay being of high resistance and having its armature normally attracted, the distant relay being of low resistance and having its armature normally at rest against a back stop, a circuit closer on the caution indicating mechanism for shunting part of the coils of the preliminary relay to increase the current in the distant wire to render the distant relay operative and a circuit closer controlled by the armature of the distant relay and included in the clear signal motor control circuit.

21. In an automatic block signaling system the combination with normally closed track circuits including track relays, and signal circuits controlled by said relays, of a distant line wire having two relays of different resistance in series but at opposite ends of a block section for controlling the clear signal circuit and both controlled by an immediate and an advance track circuit relay.

22. In an automatic block signaling system, normally closed track circuits including track relays, normally closed indicator and clearing relay circuits in multiple and each controlled by two preceding track relays, and signals controlled by said circuits.

23. In an automatic block signaling system the combination of track circuit sections, normally open lighting circuits, and normally closed clearing circuits between block stations including relays for holding the lighting circuits open, whereby upon

breaking or failure of any clearing circuit the signal in advance of the break will be lighted. 50

24. In a block signal system the combination of a signal giving home and distant indications for each block section a distant control and a preliminary relay of different resistances in series with a battery in the same line but at opposite ends of a circuit, a circuit controller operated by a second home signal for shunting out a part of the resistance included in one relay when said home signal is clear, the operation being that when all the resistance in both relays is in the line circuit the preliminary relay only will respond to the circuit of the battery, but when a part of the resistance of one relay is shunted out of the circuit both relays will respond to the current of the battery. 60 65

25. In an automatic signaling system, the combination of normally closed track circuits and normally open circuits for lighting switch lamps, associated with mechanical switch signals lighted by said lamps. 70

26. In an automatic signaling system, the combination with normally closed track circuits, normally open switch lighting circuits, normally closed clearing circuits, all so arranged that the breakage of any or all the controlling line wires, de-energizes the clearing relays causing switch lamps to burn continuously. 75

27. In an automatic block signaling system, the combination with normally closed track circuit sections including track relays, and contact fingers controlled by said relays, of signal motor circuits normally established through said contact fingers and broken 85 when the relays are de-energized and a shunt for the signal circuits closed by the back movement of said fingers, whereby the possibility of the signals remaining at clear when danger conditions exist is eliminated. 90
